UNITED STATES PATENT OFFICE.

FRANK FITZ GIBBON, OF EAST ORANGE, NEW JERSEY, AND CLARENCE FITZPATRICK,
OF BOSTON, MASSACHUSETTS.

FASTENER.

1,162,467.

Specification of Letters Patent. Patented Nov. 30, 1915.

Application filed March 9, 1915. Serial No. 13,156.

To all whom it may concern:

Be it known that we, FRANK FITZ GIBBON and CLARENCE FITZPATRICK, citizens of the United States, residing at East Orange, 5 county of Essex, and State of New Jersey, and Boston, Massachusetts, respectively, have invented certain new and useful Improvements in Fasteners, of which the following is a clear, full, and exact description.

This invention relates to fasteners of the ball and socket type, such as used for instance as glove fasteners.

The improvement particularly relates to 15 the socket portion of the fastener, and an object of the invention is to provide such socket portion with a removable button, so that buttons of different constructions and ornamentation may be applied to the same 20 socket member.

Other objects of the invention are to provide a simple and practical fastener having a removable button.

These being among the objects of the present invention, the same consists of certain features of construction and combinations of parts to be hereinafter described and then claimed with reference to the accompanying drawings illustrating desirable embodiments of the invention, and in which—

Figure 1 is a side elevation of one form of the device showing a complete ball and socket fastener applied to two layers of material to be connected; Fig. 2 is a diametrical section, the ball member being in elevation, on line 2—2 Fig. 1; Fig. 3 is a diametrical section showing a layer of material and two members of the socket portion in position before the parts are permanently secured together by an upsetting action; Fig. 4 is a perspective view of the form of screw-threaded annulus shown in Figs. 2 and 3; Fig. 5 is a side elevation of another form of the invention; Fig. 6 is a section on the line 6—6 Fig. 5, partly in elevation; Fig. 7 is a section partly in elevation of the parts shown in Fig. 6 before they are permanently secured together by upsetting; Fig. 8 is a perspective view of the annulus shown in Figs. 6 and 7; and Fig. 9 is a diametrical section of a different form of button shown in the other figures, while the buttons of the two illustrated forms of fastener are also different from

each other. Figs. 5 and 6 do not show a 55 socket member.

Referring to Figs. 1 to 4 inclusive which illustrate one form of the invention, the ball member 10 may be of any suitable type attached to one layer of material 11. The 60 socket member is attached to another layer of material 12. Said socket member comprises as shown more clearly in Fig. 2, an annulus 13 which is provided with a screw-thread 14 on its outer periphery, said annulus being provided with an internal annular flange 15 located at the lower end of the same, together with an eyelet 16 which is provided with an annular exterior flange 17, between which and the said flange 15 the 70 material 12 is secured, while the other end of said eyelet is provided with an exterior annular flange 18 which is in contact with the said flange 15 so that the latter is secured between the flange 18 and the material 75 12. The annulus 13 is shown detached in Fig. 4.

The parts of the described socket member are assembled as follows. The parts are applied to the material 12, so that the flange 80 17 of the eyelet 16 is in contact with one surface of the material 12, while the said eyelet extends through the material and through the opening 19 which is surrounded by the flange 15 of the annulus, said 85 flange 15 being in contact with the other surface of the material 12. The eyelet 16 is shown in Fig. 3 as not upset. To upset that end thereof which is within the annulus 13, said end is subjected to the action of a 90 suitable punch which upsets the inner end of the eyelet upon the anvil surface 20 at the inner side of the flange 15, with the result that the eyelet is formed with an exterior annular flange 18 which is located 95 within the annulus and in connection with the flange 17 of said eyelet binds the parts permanently together, as shown in Fig. 2.

A socket member is now provided for receiving the ball member 10, in which a securing part is upset within the annulus 13 which is exteriorly screw-threaded for the purpose of receiving an internally screw-threaded button or cap 21 shown in Figs. 1 and 2. This button may be of any suitable 100 construction, shape and ornamentation, the one shown in said figures being struck up from a piece of sheet metal so that it is pro-

vided with a rounded top 22 and an external flange 22^a which abuts against the material 12 when said button is screwed onto the annulus.

5 The embodiment of the invention shown in Figs. 5 to 8 inclusive comprises an annulus 23 provided with an external screw-thread 24 and an internal screw-thread or roughened surface 25, said annulus having 10 an external annular flange 26 at one end. Said annulus 23 is secured to the material as follows. An eyelet 27 provided with a flange 28 is introduced through an opening in the material as shown in Fig. 7, to which 15 the socket member is to be attached, said eyelet being of such length that its flange 28 is separated from the material. The unflanged end of said eyelet 27 is caused to abut preferably against the inner anvil 20 face of the closed top 23^a of said annulus 23. A suitable punch is now introduced into the eyelet 27 and against its flange 28 so as to upset the inner end of the eyelet against 25 said top 23^a and onto the screw-threaded or roughened inner surface 25 of the annulus, so that the inner end of said eyelet is formed as shown in Fig. 6 with an enlargement or flange 30 which is in intimate binding contact at 30° with the inner periphery of the 30 annulus. The upsetting action is intended to permanently secure the annulus and eyelet together and to the material of the glove or other article. The roughened or screw-threaded inner surface 25 of the annulus enters to a certain extent the outer surface of 35 the enlargement 30 which is upset within said annulus. A cap or button 29 is then screwed onto said annulus 23. The cap or button 29 shown in Figs. 5, 6 is of different 40 shape from that shown in Figs. 1 and 2.

Obviously various kinds of removable caps or button members may be employed so as to produce a different effect, and said caps or buttons may be constructed of one 45 piece of a given material or may be constructed of different materials or of more than one part. A cap or button constructed of more than one part and of different materials is shown in Fig. 9. This comprises 50 a collar 31 provided with an internal screw-thread 32, and an internal flange 33 located at the outer end of said collar, which provides an aperture 34 through which may ap-

pear an ornamental stone top 35 which is secured to the socket member when the screw 55 collar 31 is screwed onto the annulus to receive it.

The invention is susceptible of modification as parts may be omitted, added and substituted without departing from the 60 spirit and scope thereof as claimed.

What we claim as new is:—

1. A fastener, the combination of an externally screw-threaded annulus, means for 65 permanently securing the same, from its interior, to a piece of material, and a screw cap applied to said annulus.

2. In a fastener, the combination of an externally screw-threaded annulus, means for 70 permanently securing the same, from its interior, to a piece of material, said means being upset within said annulus, and a screw cap applied to said annulus.

3. In a fastener, the combination of an externally screw-threaded annulus which is 75 internally contracted at one end, an eyelet extending thereto and upset against said contracted end to secure said parts to a piece of material, and a screw cap applied to said 80 annulus.

4. In a fastener, the combination of an externally screw-threaded annulus provided with an interior anvil-surface, means extending into said annulus and upset against 85 said anvil-surface, to secure said parts to a piece of material, and an ornamental finishing button or cap screwed onto said annulus.

5. In a fastener, the combination of an annulus, means for permanently securing the same, from its interior, to a piece of material, said means being upset within said 90 annulus, and a cap secured removably to said annulus.

Signed at New York, N. Y., this 1st day of March, 1915.
